FUEL-FEEDING MECHANISM.

1,414,746.

Specification of Letters Patent.

Patented May 2, 1922.

Application filed September 8, 1917. Serial No. 190,385.

To all whom it may concern:

Be it known that we, CHARLES F. MILLER and ROBERT M. ALLEN, both citizens of the United States, and residents, respectively, of 5 Morton, Delaware County, Pa., and Swissvale Allegheny County, Pa., have made a new and useful Invention in Fuel-Feeding Mechanism, of which the following is a specification.

10 This invention relates to plunger operating mechanisms and more particularly to means for feeding fuel or like material into a retort or similar receptacle.

An object of the invention is to produce 15 a fuel feeding mechanism in which improved power actuated means are employed for actuating the fuel feeding plunger.

A further object is to produce a fuel feeding mechanism in which improved means are 20 employed for preventing fuel sifting.

A further object is to produce a fuel feeding mechanism capable of being actuated by a shaft having a constant speed of rotation and capable of being adjusted for 25 the purpose of varying the rate of feed without varying the speed of the shaft.

A further object is to produce a fuel feeding mechanism for underfeed stokers which is positive and reliable in operation and is 30 capable of manual adjustment and control.

A further object is to produce a fuel feeding mechanism for stokers in which improved means are employed for protecting the mechanism against unusual strains which 35 may be occasioned by a jamming of the fuel feeding plunger.

These and other objects, which will be made apparent throughout the further description of the invention, are attained by 40 means of apparatus embodying the features herein described and illustrated in the drawings accompanying and forming a part hereof.

In the drawings: Fig. 1 is a fragmental 45 transverse sectional view of an underfeed stoker equipped with a fuel feeding mechanism embodying our invention, and which is also shown in section.

Fig. 2 is a sectional view along the line 50 2—2 of Fig. 1.

Fig. 3 illustrates a modified arrangement of a detail of the apparatus shown in Figs. 1 and 2, and is shown in connection with a clutch member such as is illustrated in Fig. 2.

55 The apparatus illustrated as an embodi-

ment of our invention includes a plunger 4, which is capable of being reciprocated across the mouth of a fuel hopper 5 for the purpose of delivering fuel from the hopper and into and through a retort 6, the discharging edges of which are located materially above the plunger and the mouth of the hopper. The plunger shown is mounted on a horizontal table 7 across which it moves in opening and closing the mouth of the hopper and in forcing fuel into the retort. Reciprocating motion is imparted to the plunger by means of a screw feed mechanism including screw 8 and a cooperating sleeve nut 9. The sleeve is adapted to be rotated in one direction or the other for the purpose of moving the plunger either forward or back. The screw 8 is more or less loosely secured to the plunger 4, but its mode of connection is such as to prevent it from turning. The sleeve nut 9 is illustrated as consisting of a hollow tubular member provided at one end with threads for engaging the threads of the screw 8, and is journaled in a housing 10, rigidly secured to the front of the stoker. 60 A bevel-gear 11 is mounted on the forward end of the member 9 and is operatively secured to it by means of a collar 12, integrally formed on the member 9, a pin 13, and a lock nut 110 screwed onto the end of the 65 member and locked in place by any suitable means such as a set screw.

The pin 13 is so constructed and arranged that it will fail in case the apparatus is subjected to unusual strains and will thereby prevent other portions of the apparatus from being wrecked or damaged. For example, the pin 13 will shear if the plunger becomes jammed, and consequently there is no possibility of stripping the gears or the 95 screw threads or of breaking any of the co-operating parts.

In Fig. 2, we have illustrated the pin 13 and the method employed for mounting it on the gear 11 and collar 12 so that the pin 100 will shear when the apparatus is subjected to unusual strains. Both the gear and collar are provided with hard metal pin seats 14, each of which is perforated to provide an aperture through which the pin 13 is adapted to project. The seats 14 are so located on their respective mounting elements that the gear 11 may be turned about the sleeve 9 to bring the apertures in register with each other. The pin 13 may then be inserted 105 110

through the registering apertures and it may be secured in place in any suitable manner, such for example as by peening or bending over its projecting ends.

5 The sleeve 9 is provided with two thrust bearings 15 and 16, each of which is adapted to transmit longitudinal thrusts of the sleeve to the housing 10. As illustrated, one thrust bearing includes the collar 12 as an element 10 and one or more rings 17, which are loosely mounted on the sleeve 9 and are located between the collar and the adjacent thrust bearing or shoulder of the housing 10. The other bearing 16 is adapted to take up thrusts 15 in the opposite directions and includes rings 17 and a ring nut 18 screwed onto the end of the sleeve 9 and adapted to hold the rings 17 in place.

The gear 11 meshes with two bevel-gears 20 19 and 20, both of which are loosely mounted on a driving shaft 21. The shaft is journaled in suitable bearings formed within the housing 10. A clutch member 22 is mounted on the shaft 21 and is adapted to operatively 25 connect one or the other gears 19 and 20 to the shaft so that rotation in one direction or the other will be imparted to the sleeve 9. As illustrated, the member 22 consists of a sleeve splined onto the shaft 21, so that it is 30 movable longitudinally thereof. Longitudinally projecting teeth 23 are provided on one end of the member 22 and are adapted to engage similar teeth 23^a formed on the hub portion of the gear 20, when the member is 35 shifted along the shaft for the purpose of locking the gear to the shaft. A similar arrangement of teeth are provided on the opposite end of the member 22 and the gear 19. With this arrangement one or the other of 40 the gears 19 and 20 may be locked to the shaft 21, so that gear 11 will be driven in one direction or the other. It will, of course, be apparent that but one of the gears 19 and 20 is capable of being locked to the shaft at 45 a time, since the gears are so spaced with relation to the member 22 that the member passes through a neutral position in moving to disengage one gear from the shaft 21 and to lock the other gear to the shaft.

50 In the drawings we have illustrated means actuated by the movement of the screw feed mechanism for actuating the member 22 and for thereby reversing the rotation of the sleeve 9 at each end of the stroke of the plunger 4. As illustrated, a hanger 25 is mounted on the plunger 4 so that it projects downwardly. A rod 26 passes through an aperture formed in the hanger and is loosely engaged by the hanger. One end of the rod 60 26 is pivotally connected to an arm 27 of a bell crank 28, which is mounted on a vertical shaft 29. The other arm 30 of the bell crank is shown bifurcated at its end and is pivotally secured to a spring pressed member 31. 65 The member 31 is suitably mounted on a rod

32, which is pivotally mounted on the lower face of the housing 10, and a coiled spring 33 surrounds a portion of the rod and operates between a shoulder formed thereon and the member 31 so as to force the member toward the arm 30 of the bell-crank. A lever 34 is shown rigidly mounted on the shaft 29 and is provided with two downwardly projecting bell-crank-engaging lugs 35 and 35', which form a lost-motion connection between 70 the bell-crank 28 and the shaft 29. An actuating finger 36, for the member 22, is rigidly mounted on the shaft 29 and is so arranged that it is capable of shifting the clutch member into engagement with one or 75 the other of the gears 19 and 20, in response to the operation of the bell crank lever 28. Motion is imparted to the bell crank lever from the plunger 4 through the agency of 80 the hanger 25 and the rod 26. For this purpose the rod is provided with two collars 37 and 37', which are located on opposite sides of the hanger and are preferably adjustable along the rod. The collars 37 and 37' are 85 so positioned on the rod that the hanger 25 will engage one as the plunger moves toward one limit of its stroke and will engage the other as the plunger moves toward the other limit of its stroke. With this arrangement 90 the plunger will shift the position of the rod 95 at each end of its stroke and will thereby actuate the bell crank to move the member 22 out of operative engagement with the operating gears 19 or 20 of the shaft 21. The arrangement of the bell crank arm 30 and 100 the spring pressed member 31 is such, that such a movement of the bell crank will compress the spring 33 until after the member 22 is moved out of engagement with one gear and past its intermediate position. The 105 spring 33 will then expand and continue the movement of the bell crank and consequently the member 22 and thereby operatively connect the other bevel-gear to the shaft 21.

As illustrated, the housing 10 is provided 110 with an integrally formed gear casing 38, which is provided with a cover 39 and is adapted to contain lubricant for the gears 11, 19 and 20 and also for the thrust bearings 15 and 16, the bearing of sleeve 9, the 115 screw 8 and the shaft 29. The casing 38 is, of course, provided with suitable packings to prevent the leakage of lubricant around the shaft 21 and around the screw 8.

In Fig. 3, we have shown a modification 120 of the shifting mechanism for the clutch member 22. As illustrated, the rod 26 is provided with the adjustable collars 37 and 37', but each collar cooperates with a separate spring actuated sleeve 40, which is 125 adapted to engage the hanger 25 and to impart the motion of the hanger to the rod 26. As shown, a separate coiled spring 41 surrounds the shaft 26 and is located between each collar 37 and its cooperating 130

sleeve 40. The rod 26 is operatively secured to a bell crank 42, which is rigidly secured to the shaft 29 and which is provided with a projecting arm 34' corresponding to the 5 lever 34 of Fig. 2 and so arranged that it may be operated by hand. As the hanger 25 moves in one direction, for example, in the direction of the arrow, Fig. 3, it first engages the sleeve 40 and compresses the 10 spring 41 between the sleeve and the collar 37. After the spring is completely compressed the sleeve 40 positively engages the collar 37 and consequently a further movement of the hanger shifts the position of 15 the rod. The movement of the hanger, of course, continues until the member 22 is moved out of engagement with the bevel-gear which is imparting motion to the sleeve nut 9. As soon as this occurs, the hanger 20 ceases to move about the compressed spring, actuating between the sleeve 40 or the hanger, and the collar 37 continues to move the member 22 until the other bevel-gear is engaged by the member 22 and is thereby 25 operatively locked to the shaft 21. This imparts rotation in the opposite direction to the sleeve 9 and consequently moves the hanger in a direction the reverse of that indicated by the arrow. As the hanger moves 30 in this direction it engages the sleeve 41 and finally shifts the rod in the direction of its travel and thereby again shifts the position of the member 22.

In Figs. 1 and 2, we have illustrated means 35 for stopping the operation of the plunger operating mechanism. It consists in providing a latch for securing the lever 34 in such a position that the member 22 is held in the neutral or intermediate position by 40 the lugs 35 and 35'. As shown, a spring pressed latch 42 is carried by lever 34 and is adapted to engage a keeper formed in a bracket 43 of the housing 10. Both arms 34 and 34' of the mechanisms illustrated in 45 Figs. 2 and 3 respectively may be employed for manually shifting the position of the clutch member 22 and for in this way controlling the operation of the mechanism. The lever 34 may of course be provided with 50 a locking latch similar to the latch 42. Both the forward and the rear limit of the plunger's movement may be varied by shifting the positions of the collars on the rod 26.

In accordance with the requirements of 55 the patent statutes, we have illustrated and described the preferred embodiment of our invention, but we desire it to be understood that various changes, modifications, additions and omissions may be made in the apparatus illustrated without departing from the spirit and scope of the invention, as set forth by the appended claims.

What we claim is:

1. Gearing comprising in combination, a

gear case adapted to contain a lubricant, a 65 rotatable sleeve fitting closely within a corresponding portion of the casing and opening into the same, gear means within the case for alternately rotating the sleeve in opposite directions, a screw cooperating with 70 one end of the sleeve and adapted to be moved longitudinally when the sleeve is rotated and a member carried by the screw adapted to be reciprocated thereby.

2. Gearing comprising in combination a 75 gear case adapted to contain a lubricant, a sleeve rotatably mounted in the gear case and having a threaded interior portion at one end opening into the gear case to receive lubricant therefrom, thrust bearings 80 at each end of the sleeve adapted to transmit force exerted longitudinally of the sleeve in opposite directions to the case, a screw cooperating with the threaded interior portion in the sleeve adapted to be moved longitudinally by the threads thereof when the sleeve is rotated, and a member actuated by the screw and adapted to be reciprocated thereby.

3. Gearing comprising in combination a 90 gear case adapted to contain a lubricant, a sleeve rotatably mounted in the gear case and having a threaded interior portion at one end communicating with the case to receive lubricant therefrom, thrust bearings 95 at each end of the sleeve adapted to transmit to the case longitudinal thrusts of the sleeve in both directions, a screw projecting through the gear case and cooperating with the sleeve and adapted to move longitudinally thereby 100 when the sleeve is rotated, means for preventing the escape of lubricant around the screw and a member actuated by the screw and adapted to be reciprocated thereby.

4. Gearing comprising in combination, a 105 gear case adapted to contain a lubricant, a sleeve rotatably mounted in and conforming with the casing and adapted to be lubricated by the lubricant therein, gear means in the casing axially aligned with a gear mounted on the forward end of the sleeve to alternately rotate the same, a threaded screw co-operating with an interior and threaded portion of the sleeve and adapted to be reciprocated longitudinally by alternate rotations of the sleeve, the said threaded portion of the screw extending into the sleeve 110 at both extreme limits of movement and exposed to the lubricant therein, and a member actuated by the screw adapted to be reciprocated by said screw.

In testimony whereof, we have hereunto 115 subscribed our names this 1st day of September, 1917.

CHARLES F. MILLER.
ROBERT M. ALLEN.

Witness:

C. W. McGHEE.
